The ornamental design for an electric connecting terminal, as shown and described.

DESCRIPTION

FIG. 1 is a top, rear, and right side perspective view of an electric connecting terminal showing our new design;

FIG. 2 is bottom, rear, and left side perspective view thereof;

FIG. 3 is a front view thereof;

FIG. 4 is a rear view thereof;

FIG. 5 is a right side view thereof, a left side view being a mirror image thereof;

FIG. 6 is a top view thereof; and,

FIG. 7 is a bottom view thereof.

The dashed broken lines in the figures show portions of the electric connecting terminal that form no part of the claimed design. The dot-dashed broken lines in the figures show boundaries that form no part of the claimed design.
